(57) **CLAIM**

We claim the ornamental design for an adapter, substantially as shown and described.

DESCRIPTION

FIG. 1 is a perspective view of an adapter in accordance with the present design. The adapter is, for example, a display adapter that operates to adapt, convert or supply electrical signals to a computer monitor or display.

FIG. 2 is a right side view for the adapter shown in FIG. 1.

FIG. 3 is a rear view for the adapter shown in FIG. 1.

FIG. 4 is a left side view for the adapter shown in FIG. 1.

FIG. 5 is a front view for the adapter shown in FIG. 1.

FIG. 6 is a top view for the adapter shown in FIG. 1; and, FIG. 7 is a bottom view for the adapter shown in FIG. 1.
